CLARENCE H. HOWARD AND HARRY M. PFLAGER, OF ST. LOUIS, MISSOURI, ASSIGNEES
TO COMMONWEALTH STEEL COMPANY, OF ST. LOUIS, MISSOURI, A CORPORATION OF
NEW JERSEY.

CAR-TRUCK.

1,146,257.

Specification of Letters Patent. Patented July 13, 1915.

Application filed February 15, 1915. Serial No. 8,280.

To all whom it may concern:

Be it known that we, CLARENCE H. HOWARD and HARRY M. PFLAGER, citizens of the United States, residing at St. Louis, Missouri, have invented a certain new and useful Improvement in Car-Trucks, of which the following is a full, clear, and exact description, such as will enable others skilled in the art to which it appertains to make and use the same, reference being had to the accompanying drawings, forming part of this specification, in which,—

Figure 1 is a plan view of a portion of a car truck, the same embodying our improvements. Fig. 2 is an enlarged transverse section taken on the line 2—2 of Fig. 1. Fig. 3 is a perspective view of the end portion of the spring plank that is used in our improved truck.

Our invention relates generally to car trucks and more particularly to the means utilized for holding the elliptic springs in proper position upon and between the spring plank and cross bolster.

The principal object of our invention is to provide means, preferably in the form of lugs or flanges, on the spring plank and cross bolster for the purpose of holding the spring sections against transverse movement relative to said spring plank and cross bolster.

Further objects of our invention are to eliminate the spring seats ordinarily used upon cross bolsters and spring planks, thus providing more space for the brake mechanism which is associated with the truck and likewise more space for the swing hangers which support the spring plank.

With the foregoing and other objects in view, our invention consists in certain novel features of construction and arrangement of parts, hereinafter more fully described and claimed.

In the drawings, we have shown a portion of a six wheel truck, the frame of which includes wheel pieces 10, end rail 11 and parallel transoms 12 between which the usual cast metal cross bolster 13 is positioned. Positioned in suitable bearings near the ends of the transoms 12 are pins 14 from which depend the usual swing hangers 15 which support the spring plank 16 the same being formed in one piece, preferably by casting. Positioned upon the end portions of the spring plank 16 are the usual

elliptic spring sections 17 the same yielding supporting the cross bolster 13.

In our improved construction the usual bands 18 which surround the leaves of each spring section bear directly upon the spring plank and against the underside of the cross bolster 13, and in order to hold the springs against longitudinal movement, the spring plank has formed integral with it near each end a pair of transversely disposed ribs or flanges 19, and the cross bolster 13 has formed integral with it on the underside corresponding transversely disposed ribs or flanges 20 and when the parts are properly assembled the bands 18 engage between the respective pairs of ribs.

In order to hold the spring sections 17 in proper position between the spring plank and cross bolster and prevent its transverse movement relative thereto, upwardly projecting lugs 21 are formed integral with the spring plank, and corresponding downwardly projecting lugs 22 are formed integral with the cross bolster. These lugs project between the spring sections, thus holding the same against lateral movement. When two-section springs are used it is only necessary to provide a single lug, the same extending between the two sections and when more than two sections are used, lugs are provided for each space between the sections. By providing lugs between the spring sections for holding the latter in proper position, the usual spring seats which are utilized in connection with spring planks and cross bolsters are eliminated, and as a result, more space is provided to the sides of the spring plank and cross bolster for the swing hangers and for the brake rigging which is associated with the truck.

Our improved construction is comparatively simple, is applicable for use in all trucks utilizing elliptic springs, and is effective in maintaining the springs in proper position upon the spring plank and against the cross bolster.

It will be readily understood that minor changes in the size, form and construction of the various parts of our improved car truck can be made and substituted for those herein shown and described, without departing from the spirit of our invention the scope of which is set forth in the appended claims.

We claim:

1. In a car truck, a cast metal spring plank, elliptic springs positioned thereupon, lugs integral with and projecting upwardly from the spring plank for holding the springs against longitudinal and transverse movement, and a bolster supported by said springs.
2. In a car truck, a cast metal spring plank, pairs of transversely disposed ribs formed integral with the top of said spring plank near its ends for engaging parts of the springs positioned on said spring plank, and lugs integral with and projecting upwardly from the spring plank adjacent to the inner members of said pairs of ribs.
3. In a car truck, a cast metal bolster provided on its underside with transversely disposed pairs of ribs which are adapted to engage parts of the springs upon which the bolster is carried, and lugs formed integral with the underside of said bolster adjacent to the inner members of the pairs of ribs, which lugs are adapted to engage between the sections of the springs which support said bolster.
4. In a car truck, a cast metal spring plank, pairs of transversely disposed ribs formed integral with the top of said spring plank near its ends for engaging parts of the springs positioned on said spring plank, and lugs integral with and projecting upwardly from the spring plank adjacent to the inner members of said pairs of ribs.
5. In a car truck, a cast metal spring plank provided in its top surface near its ends with transversely disposed pairs of shoulders which are adapted to engage parts of the springs positioned on said spring plank, and upwardly projecting lugs formed integral with said spring plank adjacent to the inner shoulders, which lugs are adapted to engage between the sections of the springs supported by said spring plank.
6. In a car truck, a cast metal bolster provided in its underside with pairs of transversely disposed shoulders which are adapted to engage parts of the springs which support said bolster, and depending lugs integral with said bolster near the inner shoulders, which lugs are adapted to engage between the sections of the spring which support the bolster.

In testimony whereof we hereunto affix our signatures in the presence of two witnesses, this 10th day of February, 1915.

CLARENCE H. HOWARD.

HARRY M. PFLAGER.
